No. 851,536.

PATENTED APR. 23, 1907.

H. M. LINDSAY.
BOOK FOR STAMPS AND THE LIKE.

APPLICATION FILED FEB. 4, 1907.

UNITED STATES PATENT OFFICE.

HARRY M. LINDSAY, OF BALTIMORE, MARYLAND.

BOOK FOR STAMPS AND THE LIKE.

No. 851,536.

Specification of Letters Patent.

Patented April 28, 1907.

Application filed February 4, 1907. Serial No. 355,684.

To all whom it may concern:

Be it known that I, HARRY M. LINDSAY, a citizen of the United States, residing at Baltimore city, in the State of Maryland, have 5 invented new and useful Improvements in Books for Stamps and the Like, of which the following is a specification.

This invention relates to a book for use by stamp and post-card collectors, and also for 10 newspaper clippings and scraps, and has particular reference to a novel page construction and a holder to facilitate the transfer of stamps, cards, clippings or the like from one place to another without injury to either 15 the page or the devices adapted to be held thereby.

It frequently occurs that a stamp collector, for instance, is compelled to change the groups of his collection or transfer them to a 20 new book on account of an old book filling up, or to transfer the stamps from one place to another in the same book to make room for one or more stamps new to the collection. The common practice of securing the stamps 25 in place has been by means of gum strips or hinges made from paper, and in rearranging stamps after disposition in certain groups there is always a possibility of tearing and ruining the stamps which are detached for dis- 30 position in new places. Stamps are usually classed by their water marks, perforations and paper, and additions to collections require a reclassification or redisposition in accordance with certain series and kinds.

35 The improved book and holder will overcome the disadvantages heretofore encountered, and permit the several stamps to be readily changed to occupy different places on the same page or to be transferred to other 40 pages, and the several holders are of such structure that after they are secured to the stamps they need not be removed, or if it is found necessary to detach them a simple moistening operation can be pursued without 45 injury to either the holders or the stamps. The holders are of such construction that a memorandum can be made on the back surfaces thereof to indicate the particular water mark, perforation and paper of the stamps to 50 which they are attached, and are materially advantageous in this service as soaking of the several stamps in deodorized benzine to ascertain the character of the water mark and

paper and to measure the perforations will be avoided.

The preferred form of the page and holder is illustrated in the accompanying drawings, and therein:

55 Figure 1 is a perspective view of a book having therein pages embodying the features 60 of the invention. Fig. 2 is a longitudinal vertical section on the line 2—2 of one of the pages, and shown on an enlarged scale. Fig. 3 is a transverse vertical section on the line 65 3—3 of one of the pages, and also shown on an enlarged scale. Fig. 4 is a detail perspective view of a stamp showing the improved holder applied thereto. Fig. 5 is a detail perspective view of one of the holders. Fig. 6 is a sectional perspective view showing a 70 portion of one of the pages and the position of the extremities of the holder when in engagement with the page.

75 Similar characters of reference are employed to indicate corresponding parts in the views.

The numeral 1 designates a book of any suitable dimensions and comprises in its structure a plurality of pages 2. Each of the pages 2 consists of two sheets 3 and 4 of thin 80 tough paper fastened together at the edges and having small square holes 5 cut therein at regular intervals, the holes in one sheet being opposite the uncut portions of the adjacent sheet, as clearly illustrated by Fig. 3. 85 For the purpose of describing a practical form of the invention, the pages and holders, which will be hereinafter particularly referred to, will be specified for use with stamps. It will be understood, however, that the invention is not limited to this particular use, 90 as post-cards, newspaper clippings and scraps may be assembled in any desired relation in an analogous book, or one embodying the features of the invention. The openings 5 in the sheets 3 and 4 have the particular square contour shown to overcome the disadvantages in the use of slits as in collector's books now commonly constructed, and which are liable to become torn in applying and removing stamps, cards and the like, and in transferring such devices from one place to another.

95 The holder consists of a strip 6 of stiff linen of suitable length having at the center of one 100 side an adhesive substance 7. The holder is 105

slightly narrower than the width of the several square openings 5, and also materially longer than the distance between the upper and lower walls of each of said openings so as to render the holder effective in retaining a stamp or other device in positively applied position with respect to the page.

The adhesive substance at the center of the holder 6 is moistened and said holder is then applied to the middle portion of the back of the stamp, as shown by Fig. 4, both extremities of the holder being free. The lower extremity of the holder is creased, as at 8, at the lower termination of the adhesive substance or gummed portion to permit said lower extremity to be placed in one of the square openings after the upper extremity has been inserted in the same opening, so that the stamp will retain its proper place until it is desired to remove the stamp. To remove the stamp the bottom portion thereof is grasped and pulled upwardly to withdraw the lower extremity of the holder from the openings, and the upper extremity of said holder can then be readily disengaged from the opening by pulling on the stamp in a reverse direction, or downwardly. At any time desired, the holder can be easily removed from the stamp by moistening the back portion thereof adjacent to the adhesive substance or gum 7, and as the holder is formed of linen or fabric and porous, the water readily soaks through and softens the adhesive substance or gum and permits the holder to be detached from the stamp without tearing the latter.

The several holders, when inserted in the openings 5, have their extremities held between the sheets 3 and 4, as illustrated by Fig. 6, and as the openings of one sheet are opposite the uncut portions of the adjacent sheet the holders of the two sheets will not interfere with each other in applying or removing the same. After the holders have been applied, as shown by Fig. 4, the stamps can be readily transferred from one place to another in the book, or to another book having the same structure.

As hereinbefore indicated, memorandum can be applied to the back of the holder describing the water mark, perforation and paper of the stamp to serve as a permanent means for readily ascertaining these particular characteristics of each stamp without resorting to the usual methods to bring out the water mark and for measuring the perforations.

As an incidental structural feature, the pages also have slits 9 at their upper portions to receive label strips 10 which may have imprinted thereon or otherwise applied thereto the classes of stamps or the particular stamps on each page. These label strips are readily removable and may be transferred from one

page to another to correspond to the redispersion or rearrangement of the stamps, or such label strips may be replaced by other strips on the same page, as may be found necessary.

The improved book can be cheaply manufactured, is strong and durable, and will also be found exceptionally useful and convenient for the purpose for which it has been devised.

Having thus described the invention, what is claimed is:

1. A book having double pages with openings therein, the openings of one page being opposite the uncut portions of the adjacent page, and holders to removably engage said openings, and adapted to have their central portions secured to the backs of devices to be held on the pages.

2. A book having double pages with openings therein, the openings of one page being opposite the uncut portions of the adjacent page, and holders to engage said openings adapted to be removably applied to the backs of devices disposed on the pages.

3. A book comprising a plurality of pages, each made up of two different sheets secured at the edges and having openings therein, the openings in one sheet being opposite the imperforate portions of the adjacent sheet, and devices adapted to be held on the said sheets and having holders centrally secured to the back portions thereof, the upper and lower extremities of the holders being free for removable insertion in the openings.

4. A book comprising a plurality of pages having square openings therein, the openings of one page being opposite imperforate portions of the adjacent page, and devices adapted to be applied to the pages having holders secured to the backs of said devices, the upper and lower extremities of the holders being free for removable insertion in the openings and confined between the two pages when applied.

5. A book comprising a plurality of pages having openings therein, the openings of one page being opposite the uncut portions of the remaining page, and devices adapted to be applied to said pages and provided with fabric holders secured to the centers of the backs thereof, each holder having adhesive material solely on one side at the center.

6. A book comprising a plurality of pages having square openings therein, the openings of one page being opposite the uncut portions of the remaining page, and devices adapted to be applied to said pages and provided with holders formed of fabric and secured to the centers of the backs of said devices, each holder having adhesive material solely on one side at the center and the lower extremity creased adjacent to the lower termination of the adhesive material.

7. A book comprising a plurality of pages, each of which is composed of two sheets secured at the edges, the two sheets having square openings cut therein and the openings of one sheet opposite the uncut portions of the adjacent sheet, and devices adapted to be removably applied to said pages and having holders secured at the center to the backs of said devices, the holders having their up-

per and lower extremities free and held between the sheets.

In testimony whereof I have hereunto set my hand in presence of two subscribing witnesses.

HARRY M. LINDSAY.
